United States Patent Office.

JORDAN L. MOTT, OF MOTT HAVEN, NEW YORK.

Design No. 3,720, dated October 19, 1869.

DESIGN FOR A RANGE-FRONT.

The Schedule referred to in these Letters Patent and making part of the same.

To all whom it may concern:

Be it known that I, JORDAN L. MOTT, of Mott Haven, in the county of Westchester, and State of New York, have originated a new Design for a Range-Front, of which the following is a full, clear, and exact description, reference being had to the accompanying drawing, forming part of this specification, and in which—

Figure 1 represents a front view of a range, illustrating my new design;

Figure 2, a sectional profile view, taken as indicated by the line *xx* in fig. 1; and

Figure 3, a similar view, taken as denoted by the line *zz*.

Like letters refer to like parts throughout the several figures.

The design represented in the accompanying drawing is confined to the front or face of the range.

Said design embraces a flat base rim or border, *a*, swelled out in the centre, as at *a**, and rounded on its upper edge, which joins a flat moulding, *b*, that is mounted by a hollow moulding, *c*, the rounded or swelled-out portion *a**, with its portion of the mouldings *b* and *c*, being bounded on either side by small band-like projections *d d*, running upward.

Mounted on or above the hollow moulding *c*, throughout its length, is a sunken, vertically-fluted portion, *e*, surmounted by a hollow moulding, *f*, that unites it to a projecting flat fillet or band, *g*.

The mouldings immediately above this, on either side of the central rounded, or swelled-out portion hereinbefore referred to, and which is continued upward, consists of a partial "round," *h*, a "flat," *i*, a "hollow," *j*, and a rounded head, *k*, which is mounted by a flat portion or surface, *l*.

Up along, near either edge of the front, is a partially-rounded pillar-like projection, *m*.

The doors in the front of the range, on both sides

of its central portion, are of similar pattern, being of a square or parallelogramic general contour, so far as the two sides and bottom of each door is concerned, with arch-shaped tops, the borders to each of said doors being made up of mouldings *A*, the profile of which is shown in fig. 2, a flat surface, *B*, rounded off on its outer edges, to unite with the moulding *A*, and carrying a central ornament, *C*, of the figure and profile shown in figs. 1 and 2.

The central portion of the front, above the swelled or flat fillet or band portion *g*, which has on it a lip, *g**, consists of a swelled-out or bellied partial round, *h**, a similarly-bellied "flat," *i**, hollow, *j**, and swelled-out or bellied, long, under-lip-like portion, *D*.

The central front door, which is likewise of swelled-out or bellied general contour, is ornamented by an upper-lip-like portion, *E*, along its bottom, small rounded head, *n*, along its top, and has inner border or face-mouldings, *F*, the profile of which is shown in fig. 3, and which embrace a series of vertically-arranged oblong openings, *o*, edged by beading, *r*.

Above this door, on the face of the central portion of the front, are a series of curved bracket-like projections or ornaments, *s*, to a sloping-upward and outward entablature, *G*, above which is a lid or door, *H*, sloping as indicated in fig. 3, and ornamented by a moulding or mouldings, *u*, arranged to encompass or enclose the word "Defiance."

What I claim as my invention, and desire to secure by Letters Patent, is—

The design for range-fronts, herein shown and described.

JORDAN L. MOTT.
